UNITED STATES PATENT OFFICE.

JACOB KAPPLER, OF PHILADELPHIA, PENNSYLVANIA.

DESIGN FOR A LAMP SHADE AND REFLECTOR.

40,503.

Specification for Design.

Patented Feb. 8, 1910.

Application filed November 27, 1909. Serial No. 530,278. Term of patent 7 years.

To all whom it may concern:

Be it known that I, JACOB KAPPLER, a citizen of the United States, residing at Philadelphia, in the county of Philadelphia, State of Pennsylvania, have invented a new, original, and ornamental Design for Lamp Shades and Reflectors, of which the following is a specification, reference being had to the accompanying drawing, forming part thereof.

Figure 1 is a side view in elevation of the lamp shade or reflector showing my new design. Fig. 2 is a bottom plan view.

I claim:

The ornamental design for a lamp shade and reflector, as shown.

JACOB KAPPLER.
